KENNETH E. RINGLER, OF PORTLAND, OREGON

ATTACHMENT FOR PENCILS

Application filed March 3, 1928. Serial No. 258,732.

This invention relates generally to pens and pencils for writing purposes, and particularly to a special form of attachment therefor.

The main object of this invention is to provide a special form of attachment whereby a pen and pencil can be so joined that one or the other may readily be placed in an operating position.

The second object is to permit economy of time for the user by rendering it unnecessary for him to employ separate pens and pencils as is often the case.

The third object is to so construct the device as to lend itself readily to modern manufacturing methods.

The fourth object is to so construct a holder for pens that it may readily be attached to any ordinary pencil of either the fixed or lead feeding variety without interfering with the use of the eraser on the pencil or rendering same clumsy or otherwise undesirable.

These, and other objects, will become more apparent from the specification following as illustrated in the accompanying drawings, in which:

Figure 1 is a side elevation of the device showing same applied to a pencil with the pen in a retracted position. Figure 2 is a view similar to Figure 1 showing the pen in an extended position. Figure 3 is a transverse section taken along the line 3-3 in Figure 4. Figure 4 is a longitudinal section taken along the line 4-4 in Figure 3. Figure 5 is a perspective view of the pencil-holding element. Figure 6 is a perspective view of the pen-holding element. Figure 7 is a perspective view of the cover for the pen holder.

Similar numbers of reference refer to similar parts throughout the several views.

Referring in detail to the drawings, there is illustrated the ordinary pencil 10 having formed at one end a point 11 and having mounted at the other end thereof an eraser 12, such as are in common use.

The device itself consists of three principal elements, namely a pencil holder 13, a pen holder 14 and a cover 15.

The pencil holder 13 consists of a some-

what elongated curved member having the outwardly turned edges 16 and the curved fingers 17 which are adapted to partially encircle the pencil 10 and attach the device thereto.

The pen holder 14 has a curved upper side 18 and a curved lower side 19 adapted to slide upon the surface of the pencil holder 13. The top side 18 of the pen holder 14 is provided with a slot 20, a portion of whose material forms a tongue 21 whose end 22 is curved to form a latch. On the tongue 21 is also secured a button 23 for operating purposes.

The cover 15 is also curved and its under face 24 rides against the surface 18 of the pen holder 14. The edges 25 of the cover 15 are also outwardly curved to permit the edges 16 to be crimped upon same for the purpose of assembling the device.

From the edge 25 project the lugs 26 which register with the fingers 17 and prevent end-wise movement between the holder 13 and the cover 15. In the cover 15 is formed a slot 27 near one end of which is formed a pair of elevations 28 whose under sides receive the end 22 of the tongue 21. A similar elevation 29 is formed near the opposite end of the cover 15.

When assembling in the manner which is obvious from the drawings, that is, when the pen holder 14 is held between the pencil holder 13 and the cover 15, then the pen holder is slideable with relation to its adjacent elements under the control of the button 23.

Now when a pen point 30 is inserted in the end of the holder 14 and a pencil 10 is passed through the finger 17 (as shown in Figure 1) it can be seen that a slight application of power on the button 23 will push the pen point 30 to the position shown in Figure 2, and an opposite movement will restore it to the position shown in Figure 1.

In other words—the user of this device has at his command either a pen or a pencil under the control of a slight finger movement, which action becomes so natural as to be performed almost unconsciously. This renders unnecessary the carrying of the pen

or pencil in the pocket, in the mouth or behind the ear as is often the case.

While I have illustrated this form of the device as being preferable, for many reasons, 5 it must be understood, of course, that numerous changes can be made from this construction without departing from the spirit of this invention.

I am aware that many holders have been 10 constructed in which the pen point was mounted interchangeably with an eraser by telescoping certain members together, but such devices are objectionable on account of the fact that it renders impossible the use of 15 the eraser while the pen and pencil are available, or has the more serious objection that when the pen is out of use (that is when writing with a pencil and the pen point is in the air) that any ink which may remain thereon 20 is apt to flow downwardly into the holder. These devices are also objectionable on account of the fact that they require the reversal of the pencil itself, which is entirely unnecessary with my device; it is therefore not 25 my intention to cover such devices broadly, but only within the limitations of the following claims.

I claim:

1. The combination of a curved holder 30 having holding fingers formed thereon having the edges thereof flanged outwardly, an arcuate hollow pen holder whose concave side is adapted to ride against said holder, a spring latch formed in the convex side of said 35 pen holder having an operating button projecting therefrom, a cover over said pen holder adapted to bear against its convex side, said cover having a slot therein through which said button may pass, and having 40 notches formed at opposite ends of said slot which the end of said latch may engage when said pen holder is in either extreme position.

2. The combination of a pencil holder having yieldable fingers for frictionably 45 holding a pencil, a pen holder slidably mounted thereon, a cover for holding said pen holder on said pencil holder, and operating means whereby said pen holder can be moved in either direction and held in either 50 extreme position.

3. An attachment for pencils consisting 55 of an arcuate pencil holder through which a pencil may be adjustably passed, an arcuate pen holder slidably mounted on said pencil holder, a cover for holding said pen holder on said pencil holder, latch means at opposite ends of said cover, and an operating button on said pen holder for releasing said latch means and moving said pen holder between 60 its extreme positions.

4. An attachment for pencils consisting 65 of a transversely arcuate longitudinal member having pencil holding fingers extending from the edges thereof, said pencil holding member having a cover mounted upon same,

an arcuate pen holder slidably mounted between said pencil holder and cover, and spring latch means for holding said pen holder with relation to said pencil holder.

5. An attachment for pencils including an arcuate pencil holder adapted to be adjustably mounted on a pencil between the ends thereof and normally fixed with relation to the pencil, a pen holder slidably mounted on said pencil holder, a cover over said pen holder, a spring latch for said pen holder for holding same in opposite extreme positions, and a button on said pen holder for releasing said latch and moving said holder with relation to the pencil holder permitting the pencil to be normally fixed with relation to the pencil holder.

KENNETH H. RINGLER.
